WATER CLOSET

Ross A. Park, Detroit, Mich.

Application March 27, 1946, Serial No. 657,480

5 Claims. (Cl. 4—40)

1

My improvement refers particularly to means of controlling the flush valve in the water tank, which is a part of the water closet combination.

The object of my invention is to provide means at the lower level of the tank to discharge water therefrom for the purpose of flushing the bowl.

Another object of my invention is to provide automatic means within the tank for a more effective closing of the flush valve and to eliminate incidental noises which often emanate from the valve during the period of its prolonged seating.

Another object is to provide this improvement without departing from the conventional design of water closets.

Other advantages of the novel features and the combination of parts shown by me will become obvious from the description of my invention. I shall now supply said description with reference to the accompanying drawings, in which:

Fig. 1 is a view, partly in side elevation and partly in section, showing my improved water closet combination.

Fig. 2 is a sectional view of the elements of my combination taken on line *a—a* of Fig. 1.

Fig. 3 is a plan view of a detail pertaining to the mounting of a tank, which is a part of my combination, said view being taken on line *b—b* of Fig. 1.

Fig. 4 is a sectional view of a detail taken on line *c—c* of Fig. 2.

Fig. 5 is a sectional view of a detail taken on line *d—d* of Fig. 4.

Fig. 6 is a side elevation pertaining to the shaft and crank assembly, which are a part of my combination and taken on line *e—e* of Fig. 2.

Fig. 7 is a view pertaining to the mounting of a handle, said view being taken on line *f—f* of Fig. 2.

Fig. 8 is an enlarged sectional view of a discharge element of my combination as taken on line *g—g* of Fig. 2.

Fig. 9 is a sectional view taken on line *h—h* of Fig. 8.

Fig. 10 is an enlarged sectional view of elements shown in Fig. 8.

Fig. 11 is an enlarged sectional view of an automatic timer taken on line *k—k* of Fig. 2.

Fig. 12 is an enlarged sectional view of the lower part of the timer.

2

Fig. 13 is a sectional view taken on line *l—l* of Fig. 11.

Fig. 14 is a sectional view on line *m—m* of Fig. 13.

5 Similar numerals refer to similar parts throughout the several views.

In general, the water closet to which my improvement refers includes a toilet bowl 10 and a water tank 11 mounted on the flat surface 60 of the rear part 12 of said bowl. The tank is made in the conventional rectangular form but includes a horizontal partition 13 so that the interior of said tank is sub-divided into the upper chamber 14, which is the main chamber therein, and the lower auxiliary chamber 15. Water from a supply source is delivered into the upper chamber by means of a pipe 16, the supply being controlled in the usual manner by means of a float 17 operating valve 18 in the upper end of said pipe 16. Fitted into a circular aperture in said partition 13 and into a similar aperture in the bottom 19 of the lower chamber, is a cylinder 20. To insure a water-tight fit of the cylinder, a gasket 21 is employed in the junction 25 of the cylinder with the partition 13, and another gasket 22 on the underside of bottom 19, the gasket being retained in place by lock nut 23 and an intermediate annular member 24.

The cylinder, open at its upper end, is provided 30 at said end with an annular valve seat 25 for reception of a discharge valve 26, mounted on a stem 27. The stem is held in a perpendicularly slideable position by means of a bearing 28 located in the upper part of cylinder 20. At the lower end, where said cylinder forms a discharge port, the cylinder is equipped with an inwardly threaded ring 29 fitting over the outer surface of the cylinder, the ring including an inwardly extending spider 30. The latter, centrally located with respect to the cylinder, includes a tubular guide 31 embracing a liner 32. The liner is threaded externally at its lower end and is split by slots 33 longitudinally to form jaws 34, which may be compressed inwardly towards the axis of the liner by means of a threaded thimble 35. The jaws of the thimble are designed to grip the outer sheath 40 of a cable 36.

It will be noted that a plurality of baffles 37 project inwardly into the cylinder at its upper end. The baffles are tongue-shaped plates, partly 45

severed from the wall of the cylinder of which they are a part, and pushed inwardly to form an incline as shown in the drawings. This leaves an aperture 38 above each baffle. At the lower level, just above the bottom of the upper chamber 14, the wall of cylinder 20 is provided with a plurality of smaller holes 39.

I shall now describe the mechanism devised by me to operate valve 26 in cylinder 20. The mechanism is mounted on the flat top 60 of rear portion 12 of bowl 10. It includes a crank shaft 41 disposed horizontally in bearings 42, set in a housing 43 rising upwardly above said top 60. The shaft includes cranks 44 and 45 and levers 46 and 47, respectively, the purpose of the levers being to increase the throw of the cranks. Lever 47, which normally slants upwardly, as shown in Fig. 6, is connected at its upper end to cable 36 which, covered by a sheath 40, extends downwardly below top 60 into the interior of the rear portion 12 of bowl 10 and therefrom leads upwardly to be connected to stem 27 in cylinder 20, as already described.

The purpose of the cable is to serve as a means of lifting valve 26, upwardly from its seat 25 to a point 26a, indicated in dotted lines. Numeral 48 indicates a nipple on top 60 of member 12 for guidance of cable 36. A handle 49 attached to shaft 41, serves to actuate said shaft and cable 36 and by means thereof said valve 26.

Lever 46 is in turn connected to a cable 50 leading to the timing mechanism, generally indicated in Fig. 2 by numeral 51. The purpose of the timing mechanism, or timer, is to act upon the shaft and by means thereof upon valve 26 and to effect its closing with a snap, to prevent the gurgling and sizzling sounds which are ordinarily produced by closing of the valve in the last stages of the closing. The mechanism includes a cylindrical cup 52 having a uniform inner diameter, with an exception of a portion in its upper part, where the diameter expands suddenly as shown by numeral 53. Slidably disposed within the cup is a piston 54 provided with valves 55 and a vent 56. The piston is adapted to be moved downwardly towards the bottom of the cup against the tension of a spring 63, said spring being coiled around tubes 64 and 65, which are disposed in a telescopic collapsible relation with respect to each other. The last named tube 65 is affixed axially in an extension socket 66 at the bottom of cup 52. The cup is closed at the top by a plug 57, threaded into an annular member 58 skirting the upper rim of said cup. Cable 50 reaches into the cup towards piston 54 through an axial aperture in the plug and in a packing 59 centrally located therein. The plug reduced in diameter in its upper portion, screws into a bushing 61 which is secured in a circular opening in top 60 of bowl 10 by means of a lock nut 62.

When shaft 41 is turned by means of handle 49 to actuate flush valve 26, lever 46 on crank 45 being attached at its upper end to cable 50 in a way analogous to that shown in Fig. 6 with respect to lever 47, will shift piston 54 downwardly against the tension of spring 63. I wish to say at this point that the cup is filled with oil which reaches to a point above its inner expanded portion 53. When piston 54 is moved downwardly, valves 55, including ball closure 67, normally seated on funnel-like passages 68 and spaced from confining cupolas 69, permit free flow of oil upwardly through said passages 68 and aperture 70 in said cupolas. When piston 54 moves upwardly, from a level adjoining the bottom of cup 52, the

flow of oil from above the piston downwardly will be stopped by the balls but will be permitted only through vent 56, the area of which may be controlled by a pivoted cover 71. As vent 56 is comparatively small, the movement of the piston upwardly, under the action of spring 63, will be retarded till said piston reaches the level of expanded diameter 53, when oil will by-pass the piston quickly allowing the spring to expand to its full capacity.

I shall now describe the operation of my flush valve operating mechanism. It will be assumed that the upper chamber 14 of tank 11 is filled up with water. To flush the bowl 10, handle 49 on shaft 41 is depressed manually, this serving to actuate lever 47 which being connected by cable with stem 27 of flush valve 26, will lift said valve from its seat 25, permitting water contained in chamber 14 to rush downwardly into cylinder 20. A quantity of said water will strike baffles 37 and will be diverted thereby into the lower chamber 15 through apertures 38. As timer 51 is also connected to shaft 41 by means of cable 50, said cable being affixed to lever 46 on crank 45, will push piston 54 within cup 52 downwardly, allowing oil within the cup to pass upwardly through valves 55.

As will be seen from the above description, the upward push of the flush valve and the downward push of piston 54, will occur simultaneously. Assuming that handle 49 is released, spring 63 compressed by the downward movement of the piston, will expand slowly, its expansion being retarded by the limited flow of oil through vent 56 in said piston. During the period of expansion of said spring, water from chamber 14 will continue flowing into bowl 10. It will be understood that as the piston will rise upwardly, it will cause shaft 41 to turn in opposite direction to that imparted to it by the handle, which rotation, transmitted by lever 47 to cable 36, will pull valve 26 back towards its seat 25. In the last stages of the closing with but a narrow space remaining between the valve and its seat, the flow of water would cause a gurgling, choking noise. However, the piston of the timer is set in cup 52 in such a manner that it will reach, on its way upwardly, the expanded inner portion 53, at the moment when the passage between valve 26 and its seat 25 is restricted dangerously enough to produce said objectionable noises. At this moment oil within the cup will by-pass piston 54 around its rim allowing spring 63 to expand suddenly. Cable 50 under the impulse of said upward shift of piston 54 will exert its thrust against lever 46, causing an equally sudden closure of flush valve 26.

It will be remembered that during the flushing period a quantity of water has been directed into chamber 15. After the flushing operation has been completed, said water will flow out through holes 39 into cylinder 20 and therefrom into bowl 10 to effect a more efficient water seal by raising the contents of water still remaining in the bowl to a somewhat higher level.

To conclude the description of my improved water closet combination, I wish to point out some minor details thereof. One of them pertains to the splined end 72 of shaft 41 where it fits into socket 73 of handle 49, the handle and the shaft being held together by means of a screw 74, as shown in Fig. 7.

Similar adjustment is desirable with respect to the seating of levers 46 and 47, as shown in

Fig. 6, the splined member within the dip of the respective crank being shown by numeral 75.

Another detail pertains to the mounting of tank 11 on surface 60, which is a part of bowl 10. The opening 76 for the reception of the lower part of cylinder 20 is oblong and equipped with a gasket 19. It is on this gasket that the bottom of tank 11 may rest. This construction allows the whole tank to be shifted forwardly or rearwardly with respect to bowl 10. A T-slot 77 in the bottom of the tank serves to accommodate the head of a screw 78. The screw passes downwardly through top 60 to be secured below by a nut. The shifted position of the tank is shown in Fig. 4 by numeral 11a. Inside the tank, pipes 80 are provided to take care of overflow of water therein, said pipes leading downwardly to discharge water into the bowl.

It will be understood that some changes may be made in the construction of my improved water closet without departing from the inventive principle disclosed therein.

What I, therefore, wish to claim is as follows:

1. In a water closet including a bowl and a tank with water for flushing said bowl, said tank having an upper and a lower chamber, means to admit water from a source of supply to the upper chamber, a float valve to control admission of water to said chamber, a cylindrical member seated in the bottom of the upper chamber and including a flush valve therein, a cable adapted to be operated by a handle to open said flush valve, baffle means within the cylinder and apertures in the wall thereof and above said baffles to divert a part of the volume of water into the lower chamber on opening of said flush valve, automatic means responsive to the operation of the handle to close the flush valve suddenly after a lapse of time and outlet means from the lower part of the cylinder to allow outflow of water from the lower chamber into the bowl after the closing of the flush valve.

2. In a water closet including a bowl and a tank with water for flushing of the bowl and including an upper and a lower chamber, means to admit water into the upper chamber from a source of supply, a float valve to control the level of water so admitted thereto, a cylindrical outlet tube in the bottom of the upper chamber and leading to the bowl, a flush valve seated in the top of the tube, cable means to operate said flush valve, lever means to actuate said cable to open said flush valve to release water from the upper chamber, baffle means within the tube and apertures in the wall of the tube above said baffles but below the bottom of the upper chamber to divert a part of the volume of water into the lower chamber, automatic means to close the valve suddenly after a retarded closing period, and restricted outlet means in the wall of the tube to allow outflow of water from the lower chamber into the bowl after the closing of the flush valve.

3. In a water closet including a bowl and a tank with water to flush the bowl, said tank including an upper chamber and an auxiliary lower chamber, means to admit water to said upper chamber from a source of supply to a desired level within said last named chamber, a cylindrical outlet tube in the bottom thereof, said tube extending downwardly to open into the bowl, a flush valve seated within the upper portion of the tube, cable means extending into said tube from below to operate said flush valve in order to release water from the upper chamber into said tube, the tube being provided with a plu-

rality of openings in its wall at a level below the bottom of the upper chamber, and a plurality of baffles within just below said openings to divert a part of the volume of water passing downwardly from the upper chamber into the lower chamber, a shaft mounted below the tank and having a lever attached to the cable means leading to and being affixed to the flush valve, handle means on said shaft to actuate said cable means for the purpose of opening the flush valve, automatic means responsive to the rotation of the shaft in its valve opening phase to close said valve suddenly after a retarded closing period, and restricted outlet means in the lower portion of said tube to permit outflow of water from the lower chamber into the bowl after the closing of the flush valve.

4. In a water closet including a bowl and a tank with water for flushing said bowl, said tank having an upper and a lower chamber, means to admit water from a source of supply to the upper chamber, a float valve to control admission of water to said chamber, a cylindrical member disposed within the bottom of the upper chamber and extending downwardly through the lower chamber, a flush valve seated in the upper end of the cylindrical member, a cable adapted to be operated by a handle located outside the tank to open said flush valve, baffle means within the cylinder, below the location of said flush valve, the cylinder wall being provided with openings therein, above the baffles, to divert a part of the volume of water into the lower chamber on opening of said flush valve, automatic means responsive to the operation of the handle to close the flush valve suddenly after a lapse of time and outlet means from the lower part of the cylinder to allow outflow of water from the lower chamber into the bowl after the closing of the flush valve.

5. In a water closet including a bowl and a tank with water to flush the bowl, said tank including an upper chamber and an auxiliary lower chamber, means to admit water to said upper chamber from a source of supply to a desired level within said last named chamber, a cylindrical outlet tube in the bottom thereof, said tube extending downwardly to open into the bowl, a flush valve seated within the upper portion of the tube, cable means extending into said tube from below to operate said flush valve in order to release water from the upper chamber into said tube, the tube being provided with a plurality of openings in its wall at a level below the bottom of the upper chamber, and a plurality of baffles within, just below said openings to divert a part of the volume of water passing downwardly from the upper chamber into the lower chamber, a shaft mounted below the tank and having a lever attached to the cable means leading to and being affixed to the flush valve, handle means on said shaft to actuate said cable means for the purpose of opening the flush valve, automatic means responsive to the rotation of the shaft in its valve opening phase to close said valve suddenly after a retarded closing period, said automatic means including a vertical oil filled cylinder disposed below said shaft, a piston axially disposed within the cylinder, a coiled spring under the piston, an elongated member at one end connected to a crank on the shaft and at the other end connected to the upper surface of the piston, valve means in the piston to allow quick passage of oil on the downward movement of the piston against the tension of the spring, and a restricted opening in said piston for a retarded passage of oil

70
75

on the return movement of the piston under the action of the spring, said cylinder including an upper portion of increased inner diameter to permit rapid movement of the piston on reaching said portion, and restricted outlet means in the lower portion of said tube to permit outflow of water from the lower chamber into the bowl after the closing of the flush valve.
